UNITED STATES PATENT OFFICE

2,053,134

FREEZING TRAY AND RELEASE DEVICE
THEREFORWilliam Dalton, Schenectady, N. Y., assignor to
General Electric Company, a corporation of
New York

Application August 27, 1935, Serial No. 38,047

12 Claims. (Cl. 62—108.5)

My invention relates to freezing trays and more particularly to release devices therefor.

Freezing trays, which are ordinarily shallow open top rectangular receptacles, are provided for refrigerating machines and especially those designed for household use. The freezing tray is provided with a series of partitions which divide the same into a series of relatively small compartments and the compartments are filled with water or other substances to be frozen. The freezing tray is then placed on a supporting surface of a cooling unit, such as a refrigerant evaporator, in order to freeze the contents of the tray. Difficulty has heretofore been encountered in removing such freezing trays from the surface of the evaporator, or other cooling unit, on which it is supported since there is ordinarily sufficient moisture on the surface of the cooling unit or the tray when the tray is placed on the cooling unit, to form an ice bond between the tray and the contacting surface of the cooling unit.

It is an object of my invention to provide a freezing tray having an improved arrangement for breaking the ice bond between the tray and the adjacent surface of the cooling unit prior to removal of the tray therefrom.

Further objects and advantages of my invention will become apparent as the following description proceeds and the features of novelty which characterize my invention will be pointed out with particularity in the claims annexed to and forming a part of this specification.

For a better understanding of my invention, reference may be had to the accompanying drawing in which Fig. 1 is a perspective view, partly in section, of a portion of a refrigerant evaporator and a freezing tray mounted thereon, the freezing tray being provided with a release device embodying my invention, and Fig. 2 is a perspective view, partly in section, of a refrigerant evaporator and a freezing tray mounted thereon, the freezing tray being provided with a modified form of a release device embodying my invention.

Referring to the drawing, in Fig. 1 I have shown a shallow open top rectangular freezing tray 10, made of sheet metal which is provided with a removable partition assembly 11 dividing the interior thereof into a series of compartments in which cubes of ice, or the like, 12 are formed. A depending lip 10a is formed on the upper front edge of the freezing tray 10 and forms a convenient handle therefor. The freezing tray 10 is mounted on a flat horizontal supporting surface 13 of a refrigerant evaporator 14, such as is used in a household type refrigerator. The evaporator

14 includes a smooth inner sheet 15a and a corrugated outer sheet 15b. The sheets 15a and 15b are arranged with the portions of the sheet 15b between the corrugations therein in contact with the sheet 15a and the sheets are welded, or otherwise rigidly secured, together throughout the lengths of the contacting portions thereof. Vaporizable liquid refrigerant is supplied to the passages in the evaporator 14 formed by the corrugations in the sheet 15b and the cooperating inner sheet 15a from a suitable source. The refrigerant circulating through the passages of the evaporator 14 is vaporized by the absorption of heat from the contents of the freezing tray 10 and the surrounding air within the compartment in which the evaporator is mounted.

The freezing tray 10 is provided with a device for releasing the same from the supporting surface 13 of the evaporator 14 when it is desired to remove the freezing tray 10 from the evaporator. There is ordinarily sufficient moisture either on the exterior surface of the freezing tray 10 or on the supporting surface 13 of the evaporator 14, when the freezing tray is positioned within the evaporator, that a bond of ice is formed between the bottom of the freezing tray 10 and the supporting surface 13 of the evaporator, thus making it desirable to provide some easily manipulated arrangement for freeing the freezing tray from the surface of the evaporator. In the form of my invention, illustrated in Fig. 1, the release device includes a strip 16 of stiff resilient sheet metal, such as phosphor-bronze. I prefer to use phosphor-bronze since it not only has the desired characteristics of resilience and stiffness but also resists corrosion. The strip of metal 16 includes opposed C-shaped portions 17 and 18 and an integral depending tongue 19 which is spot welded, or otherwise rigidly secured, to the exterior surface of the front wall of the freezing tray 10 adjacent the upper edge thereof. The central sections 17a and 18a of the C-shaped portions 17 and 18 of the resilient strip 16 are reduced in cross section in order that the maximum bending will take place in the sections 17a and 18a. The lower ends 20 and 21 of the strip 16 are bent upwardly being arranged side by side, and are slidably engaged by a U-shaped sheet metal guide 22 which holds them in position. The ends 23 and 24 of the guide 22 extend laterally therefrom and are spot welded, or otherwise rigidly secured, to the lower portion of the exterior surface of the front wall of the freezing tray 10. The guide 22 thus serves to hold the resilient strip 16 in a substantially elliptical configuration in which the bottom

ends 20 and 21 of the strip 16 are bent upwardly being arranged side by side, and are slidably engaged by a U-shaped sheet metal guide 22 which holds them in position. The ends 23 and 24 of the guide 22 extend laterally therefrom and are spot welded, or otherwise rigidly secured, to the lower portion of the exterior surface of the front wall of the freezing tray 10. The guide 22 thus serves to hold the resilient strip 16 in a substantially elliptical configuration in which the bottom

loop portions 25 and 26 thereof are positioned adjacent the lower edge of the front wall of the freezing tray 10 and in the plane of the bottom of the tray. The portions 25 and 26 of the sheet metal strip 16 are thus ordinarily in contact with the supporting surface 13 of the evaporator 14.

When it is desired to remove the freezing tray 10 from the surface 13 of the evaporator 14, the frozen bond between the bottom of the tray 10 and the surface 13 of the evaporator may be readily broken by grasping the portions 17 and 18 of the resilient strip 16 and flexing them inwardly toward each other. This causes the strip 16 to assume a configuration in which the portions 17 and 18 are somewhat straightened, the maximum bending occurring in the central sections 17a and 18a, so that the rounded bottom portions 25 and 26 of the resilient strip 16 are extended below the bottom of the freezing tray. As a consequence, the front of the freezing tray 10 is lifted from the surface 13 of the evaporator 14 by the downward movement of the portions 25 and 26 of the resilient strip 16 which bear against the adjacent surface of the evaporator and the frozen bond between the freezing tray and the evaporator is thus broken. It will be noted that the movement of the strip 16 during flexure thereof results in what may be termed a "toggle action". Each of the C-shaped portions 17 and 18 of the resilient strip 16 is in effect a toggle, the upper ends acting as fixed pivots, the sections 17a and 18a acting as movable joints, the parts of the C-shaped portions on each side of the sections 17a and 18a acting as toggle links and the lower portions 25 and 26 exerting a resultant downward pressure due to the toggle action. It will thus be seen that I have provided an arrangement in which the leverage of a toggle mechanism is had while at the same time a simple, rugged, easily manufactured device is utilized in which the conventional type of pivots are omitted. The latter feature is important since if conventional pivots including pivot pins and hubs were used, they would become clogged with ice and frost.

In Fig. 2, I have illustrated a modified form of release device embodying my invention. This release device is illustrated in conjunction with a rectangular open top metallic freezing tray 10 provided with a partition assembly 11 and having ice cubes 12 therein, which is identical with the freezing tray 10 and partition assembly therefor illustrated in Fig. 1. The freezing tray 10 shown in Fig. 2 is mounted on a supporting surface 13 of a refrigerant evaporator 14 made up of a smooth inner sheet 15a and a corrugated outer sheet 15b which is identical with the evaporator 14 shown in Fig. 1. The release device illustrated in Fig. 2 includes a C-shaped strip 27 of stiff resilient sheet metal such as phosphor-bronze and having a reduced central section 27a. The upper end 28 of the resilient strip 27 is spot welded or otherwise rigidly secured to the exterior surface of the front wall of the freezing tray 10 adjacent the upper edge thereof. The lower end 29 of the resilient strip 27 extends upwardly and is slidably engaged by a U-shaped sheet metal guide 30 which holds it in position. The ends of the U-shaped guide 30 extend laterally therefrom, as indicated at 31, and are spot welded or otherwise rigidly secured to the lower portion of the exterior surface of the front wall of the freezing tray 10. The guide 30 thus serves to hold the resilient strip 27 in a substantially C-shaped configuration in which the bottom looped portion 32 thereof is positioned adjacent the lower edge of the front wall of the freez-

ing tray 10 and in the plane of the bottom of the tray. The bottom portion 32 of the resilient strip 27 is ordinarily in contact with the supporting surface 13 of the evaporator 14.

When it is desired to remove the freezing tray 10 from the surface 13 of the evaporator 14, the frozen bond between the bottom of the tray 10 and the surface 13 of the evaporator may be readily broken by flexing the resilient strip 27 inwardly, the maximum bending occurring in the central section 27a. The resilient strip 27 is thus caused to assume a configuration in which the central portion thereof is somewhat straightened so that the rounded bottom portion 32 thereof is extended below the bottom of the freezing tray 10 by the toggle action described above. As a consequence, the front of the freezing tray 10 is lifted from the surface 13 of the evaporator 14 by the downward movement of the portion 32 of the resilient strip 27 which bears against the adjacent surface of the evaporator, and the frozen bond between the freezing tray and the evaporator is thus broken.

Although I have shown a particular embodiment of my invention in connection with a rectangular metallic freezing tray, I do not desire my invention to be limited to the particular form shown, but wish to cover all modifications within the spirit and scope of my invention.

What I claim as new and desire to secure by Letters Patent of the United States is:

1. A freezing tray for ice cubes or the like having bottom and side walls and a release device therefor adapted to free said freezing tray from an adjacent surface of a cooling unit, said release device comprising a strip of stiff resilient sheet metal, means for securing a portion of said strip to the exterior surface of one of said side walls of said freezing tray, and means remote from said securing means engaging said strip for maintaining the same in a configuration in which a second portion thereof lies adjacent an edge of one of said side walls of said freezing tray, said strip being deformable to a configuration in which said second portion thereof extends laterally beyond said edge of said side wall of said freezing tray and in a position to bear against an adjacent surface of the cooling unit.

2. A freezing tray for ice cubes or the like having bottom and side walls and a release device therefor adapted to free said freezing tray from an adjacent surface of a cooling unit, said release device comprising a strip of stiff resilient sheet metal having a section of reduced cross section, means for securing a portion of said strip on one side of said section of reduced cross section to the exterior surface of one of said side walls of said freezing tray, and means engaging said strip on the opposite side of said section of reduced cross section for maintaining said strip in a configuration in which a second portion thereof lies adjacent an edge of one of said walls of said freezing tray, said strip being deformable to a configuration in which said section of reduced cross section is flexed laterally and in which said second portion of said strip extends laterally beyond said edge of said side wall of said freezing tray and in a position to bear against an adjacent surface of the cooling unit due to toggle action, the maximum deformation in said strip occurring at said section of reduced cross section.

3. A freezing tray for ice cubes or the like having bottom and side walls and a release device therefor adapted to free said freezing tray from

an adjacent surface of a cooling unit, said release device comprising a strip of stiff resilient sheet metal, means for securing a portion of said strip to the exterior surface of one of said side walls of said freezing tray, and means including a 5 guide mounted on said freezing tray and slidably engaging said strip for maintaining said strip in a configuration in which a second portion thereof lies adjacent an edge of one of said side walls of said freezing tray, said strip being deformable to a configuration in which said second portion thereof extends laterally beyond said edge of said side wall of said freezing tray and in a position to bear against an adjacent surface 10 of the cooling unit.

4. A freezing tray for ice cubes or the like having bottom and side walls and a release device therefor adapted to free said freezing tray from an adjacent surface of a cooling unit, said release device comprising a strip of stiff resilient sheet metal having a substantially C-shaped portion, means for securing said strip to the exterior surface of one of said side walls of said freezing tray adjacent one end of said C-shaped portion thereof, and means engaging said strip for maintaining the same in a configuration in which a part of said C-shaped portion of said strip lies adjacent an edge of one of said side walls of said freezing tray, said C-shaped portion of said strip being deformable to a configuration in which said part thereof extends laterally beyond said edge of said side wall of said freezing tray and in a position to bear against an adjacent surface of the cooling unit.

5. A freezing tray for ice cubes or the like having bottom and side walls and a release device therefor adapted to free said freezing tray from an adjacent surface of a cooling unit, said release device comprising a strip of stiff resilient sheet metal having a substantially C-shaped portion, the central section of said C-shaped portion having a reduced cross section, means for securing said strip to the exterior surface of one of said side walls of said freezing tray adjacent one end of said C-shaped portion thereof, and means engaging said strip for maintaining the same in a configuration in which a part of said C-shaped portion of said strip lies adjacent an edge of one of said walls of said freezing tray, said C-shaped portion of said strip being deformable to a configuration in which said section of reduced cross section is flexed laterally and said part of said C-shaped portion extends laterally beyond said edge of said side wall of said freezing tray and in a position to bear against an adjacent surface of the cooling unit due to toggle action.

6. A freezing tray for ice cubes or the like having bottom and side walls and a release device therefor adapted to free said freezing tray from an adjacent surface of a cooling unit, said release device comprising a strip of stiff resilient sheet metal having a substantially C-shaped portion, means for securing the upper end of said C-shaped portion of said strip to an exterior surface of the front wall of said freezing tray adjacent the upper edge thereof, and means engaging said strip for maintaining the same in a configuration in which the lower part of said C-shaped portion thereof lies adjacent the bottom edge of the front wall of said freezing tray, said strip being deformable to a configuration in which said lower part thereof extends downwardly beyond said lower edge of said front wall of said freezing

tray and in a position to bear against an adjacent surface of the cooling unit.

7. A freezing tray for ice cubes or the like having bottom and side walls and a release device therefor adapted to free said freezing tray from an adjacent surface of said cooling unit, said release device comprising a strip of stiff resilient sheet metal, means for securing a portion of said strip to the exterior surface of one of said side walls of said freezing tray, and means including a U-shaped guide extending about said strip adjacent one end thereof and slidably engaging the same for maintaining said strip in a configuration in which a second portion thereof lies adjacent an edge of one of said side walls of said freezing tray, said strip being deformable to a configuration in which said second portion thereof extends laterally beyond said edge of said side wall of said freezing tray and in a position to bear against an adjacent surface of the cooling unit.

8. A freezing tray for ice cubes or the like having bottom and side walls and a release device therefor adapted to free said freezing tray from an adjacent surface of a cooling unit, said release device comprising a strip of stiff resilient sheet metal having a substantially C-shaped portion, means for securing said strip to the exterior surface of one of said side walls of said freezing tray adjacent one end of said C-shaped portion, and means including a U-shaped guide mounted on said freezing tray and extending about the opposite end of said C-shaped portion of said strip for maintaining said strip in a configuration in which a part of said C-shaped portion thereof lies adjacent an edge of one of said side walls of said freezing tray, said strip being deformable to a configuration in which said part of said C-shaped portion extends laterally beyond said edge of said side wall of said freezing tray and in a position to bear against an adjacent surface of the cooling unit.

9. A freezing tray for ice cubes or the like having bottom and side walls and a release device therefor adapted to free said freezing tray from an adjacent surface of a cooling unit, said release device comprising a strip of stiff resilient sheet metal having a substantially elliptical shape with the ends thereof extending inwardly side by side, means including an integral tongue extending from the top of said strip for securing the same to the exterior surface of the front wall of said freezing tray adjacent the upper edge thereof, and means including a U-shaped guide mounted on said freezing tray and extending about said ends of said strip for maintaining said strip in a configuration in which the lower portions thereof lie adjacent the bottom edge of said front wall of said freezing tray, said strip being deformable to a configuration in which said bottom portions thereof extend downwardly beyond said lower edge of said front wall of said freezing tray and in a position to bear against an adjacent surface of the cooling unit.

10. A freezing tray for ice cubes or the like having bottom and side walls and a release device therefor adapted to free said freezing tray from an adjacent surface of a cooling unit, said release device comprising a strip of stiff resilient sheet metal having a substantially elliptical shape with the ends thereof extending inwardly side by side, the central sections of the side portions of said strip having a reduced cross section, means including an integral tongue extending from the top of said strip for securing the same to the exterior surface of the front wall of

- said freezing tray adjacent the upper edge thereof, and means including a U-shaped guide mounted on said freezing tray and extending about said ends of said strip for maintaining said strip in a configuration in which the lower portions thereof lie adjacent the bottom edge of said front wall of said freezing tray, said strip being deformable to a configuration in which said central sections thereof are flexed laterally and in which said bottom portions of said strip extend downwardly beyond said lower edge of said front wall of said freezing tray and in a position to bear against an adjacent surface of the cooling unit due to toggle action.
15. 11. A freezing tray for ice cubes or the like having bottom and side walls and a release device therefor adapted to free said freezing tray from an adjacent surface of the cooling unit, said release device comprising a C-shaped strip of stiff resilient sheet metal, means for securing the upper end of said C-shaped strip to the exterior surface of the front wall of said freezing tray adjacent the upper edge thereof and in a position in which said C-shaped strip extends outwardly from said freezing tray, and means including a U-shaped guide mounted on said freezing tray and surrounding the lower end of said C-shaped strip for maintaining said strip in a configuration in which the lower portion thereof lies adjacent the lower edge of said front wall of said freezing tray, said strip being de-

formable to a configuration in which said lower portion thereof extends downwardly below said lower edge of said front wall of said freezing tray and in a position to bear against an adjacent surface of the cooling unit. 5

12. A freezing tray for ice cubes or the like having bottom and side walls and a release device therefor adapted to free said freezing tray from an adjacent surface of the cooling unit, said release device comprising a C-shaped strip 10 of stiff resilient sheet metal, means for securing the upper end of said C-shaped strip to the exterior surface of the front wall of said freezing tray adjacent the upper edge thereof and in a position in which said C-shaped strip extends 15 outwardly from said freezing tray, said strip having a central section of reduced cross section, and means including a U-shaped guide mounted on said freezing tray and surrounding the lower end of said C-shaped strip for maintaining said 20 strip in a configuration in which the lower portion thereof lies adjacent the lower edge of said front wall of said freezing tray, said strip being deformable to a configuration in which said central section is flexed inwardly and in which said 25 lower portion of said strip extends downwardly below said lower edge of said front wall of said freezing tray and in a position to bear against an adjacent surface of the cooling unit due to toggle action.

30 WILLIAM DALTON.
